220,920

DOUBLE ENDED CUTTING INSERT

Burton L. Cochran, North Canton, Ohio, assignor to The
Warner & Swazey Company, Cleveland, Ohio

Filed Feb. 18, 1970, Ser. No. 21,483

Term of patent 14 years

Int. Cl. D15—99

U.S. Cl. D54—6

FIG. 1

FIG. 2

FIG. 3

FIG. 4

FIG. 1 is a perspective view of a double ended cutting insert embodying my new design.

FIG. 2 is a top plan view thereof.

FIG. 3 is an end elevation taken from the left of FIG. 2.

FIG. 4 is a side elevation showing one side of my new design. The side of my new design, shown in FIG. 4, is identical with the opposed side thereof.

I claim:

The ornamental design for a double ended cutting insert, as shown and described.
